UNITED STATES PATENT OFFICE.

OSCAR R. MANVILLE, OF BRECKENRIDGE, MISSOURI.

DRAFT ATTACHMENT FOR VEHICLES.

1,124,484.

Specification of Letters Patent. Patented Jan. 12, 1915.

Application filed April 22, 1914. Serial No. 833,763.

To all whom it may concern:

Be it known that I, OSCAR R. MANVILLE, a citizen of the United States, residing at Breckenridge, in the county of Caldwell 5 and State of Missouri, have invented a new and useful Draft Attachment for Vehicles, of which the following is a specification.

This invention relates to improvements in the draft portions of vehicles and more 10 particularly to a wagon tongue and accompanying parts.

The object of the present invention is to provide a vehicle tongue formed of metal and so constructed as to be light in weight 15 and cheap to manufacture so as to compete with tongues formed of other materials.

A further object is to provide a vehicle tongue and swingletrees therefor formed of spaced angle iron members which will withstand 20 hard usage and will not deteriorate in any marked degree with age.

Another object is to improve generally and enhance the utility of those devices to which the present invention appertains.

25 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

35 In the drawings accompanying this specification and forming a part thereof, the preferred embodiment of my invention is illustrated, in which:—

Figure 1 is a top plan view of the vehicle 40 tongue and accompanying parts. Fig. 2 is a view in side elevation thereof. Fig. 3 is a cross sectional view taken on the line 3—3 of Fig. 2. Fig. 4 is a cross sectional view taken on the line 4—4 of Fig. 1. Fig. 5 is a 45 top plan view of one portion of the whiffle-tree illustrating the same as being applied to the shafts of a vehicle. Fig. 6 is a cross sectional view taken on the line 6—6 of Fig. 1. Fig. 7 is a cross sectional view taken 50 on the line 7—7 of Fig. 1.

Referring to the drawings in which similar reference numerals designate corresponding parts throughout the several views, the tongue proper, 5, is formed by two angle 55 members 6 and 7 secured together and held in fixed relation by the spacing blocks 8.

Suitable rivets 9 project through the side walls of the angle members and the spacing blocks, to thus rigidly hold the angle members in the form of a channel bar.

60

The rear extremities of the angle members are outwardly curved as at 11. The extremities of the angle bars are secured to the curved bridge member 12 by suitable means 13. The opposite extremities of the angle bars taper to a point over which extends a cap 14 and from which projects a rim 15. A tie or brace rod 16 projects through the front extremity of the cap 14 and is provided with the tightening nut 17 thereon. 70 The tie rod is in the nature of a truss or brace bar and projects rearwardly and centrally beneath the angle bars, passing through suitable grooves 18 in the spacing blocks and projects above the top surface 75 of the rear spacing block 19. The rear extremity of the truss rod is provided with the eye 20 through which a pivot bolt 21 extends, to securely anchor this extremity of the strut bar in place and allowing the requisite tension to be exerted within the bar by adjusting the nut 17.

A pair of connecting rods 22 are rigidly secured at 23 to the bridge member 12, and project therebeyond to form the attaching 85 arms 24 through which the apertures 25 extend. The apertures 25 are provided for the reception of bolts or other securing means whereby the tongue is secured to the vehicle. The front extremities 26 of the connecting 90 rods are rigidly secured to the angle members 6 and 7 as will be clear by referring to Fig. 2.

The rear spacing block 19 through which the pivot bolt 21 extends holds the angle 95 members in spaced relation at this point and directly above the same is mounted the doubletree 27. The doubletree is also formed of the angle members 29 which are held in spaced relation by suitable blocks 30. The swingletrees 31 are also formed of spaced angle members 32 and are provided with spacing blocks 33. The usual and suitable clamp 34 extends through the swingle and double trees and provides for their 100 pivotal securing. Each swingletree as illustrated in Fig. 5 comprises the central spacing block 33 and the end blocks 34. The angle members 32 of which the swingletree is formed converge at their extremities 110 to thus materially strengthen the same. Secured to and projecting outwardly from the

end spacing blocks 34 are the pins 35 which acting in conjunction with the rotating latch members 36 are adapted to lock or secure the traces to the swingletrees in such manner as to prevent their accidental detachment. In order to strengthen the bolt 21, the bracket 37 is provided, the same being offset as at 38, allowing it to rigidly engage the upper extremity of the bolt 21 and the rear bridge member 12 without interfering with the movement of the whiffle-tree. The forward extremity of the bracket 37 is upwardly curled as at 39, allowing a strap or allied flexible member to be secured thereto.

Having thus fully described my invention, what I claim is:—

1. An article of the class described, comprising a pair of angle members, means secured thereto and holding the same in spaced relation, a curved bridge member rigidly secured to the extremities of said angle members, connecting rods secured to said angle members and the said bridge member, said connecting rods projecting rearwardly and forming attaching arms, and a truss rod extending longitudinally beneath the angle members and bracing the same in a vertical plane.
2. An article of the class described, comprising a pair of angle members, means secured thereto and holding the same in spaced relation, a curved bridge member rigidly secured to the extremities of said angle members, connecting rods secured to said angle members and the said bridge member, said connecting rods projecting rearwardly and forming attaching arms, a truss rod extending beneath said angle members contacting with the lower surfaces of

said spacing means, said truss rod projecting beyond the front extremities of said angle members, and tightening means positioned upon the front extremity of said truss rod, engaging the front extremity of the angle members, adapted to adjust the tension within said truss rod to thus brace the angle members in a vertical plane.

3. An article of the class described, comprising a pair of angle members, spacing blocks extending therebetween and holding the same in spaced and rigid relation, means secured to the rear extremities of the angle members for the attachment of the same to a vehicle, a cap positioned upon the front extremities of the angle members, and a truss rod projecting through the said cap, passing beneath and contacting with the spacing blocks and anchored to the rear portions of said angle members, and means positioned upon the truss rod beyond and contacting with said cap for the adjustment of the strut bar tension.

4. A vehicle tongue comprising elongated members, means disposed therebetween and secured thereto, holding the same in spaced relation, means secured to and projecting from the sides of the said members adapted to secure the same to a vehicle, and a truss rod extending axially beneath the said elongated members and contacting with the said spacing means thereof and bracing the elongated members in a vertical plane.

In testimony that I claim the foregoing as my own, I have hereto affixed my signature in the presence of two witnesses.

OSCAR R. MANVILLE.
